CORNER POCKET MOUNTING DEVICE

Filed Oct. 12, 1931

UNITED STATES PATENT OFFICE

ALBERT W. ENGEL, OF CHICAGO, ILLINOIS

CORNER POCKET MOUNTING DEVICE

Application filed October 12, 1931. Serial No. 568,287.

The purpose of this invention is to provide an improved device in the nature of a pocket for securing photographs, pictures, cards and the like to any suitable mounting in a convenient, artistic manner, by affixing to the mount several of these pocket devices in position to register with the corners of the card or picture, and inserting the corners of the picture in the respective pockets. Another object is to provide a pocket of this character which shall be transparent and therefore substantially invisible, so that it shall not obstruct or cover any portion of the picture which it overlies. A further object is to adapt a pocket of this character for securing the card or picture either temporarily and removable, or permanently at the option of the user.

In the drawings:

Figure 1 is a plan view showing a picture as it appears when secured to a mount by devices embodying this invention.

Figure 2 is a plan view showing the blank of transparent material employed in the manufacture of the device, and indicating how such blanks may be cut from a continuous strip.

Figure 3 is a plan view of the blank after the folding operation.

Figure 4 is a plan view of the blank showing the same mounted upon its paper backing ready for use, and constituting a completed mounting device in accordance with this invention.

Figure 5 is a plan view of the device viewed from the under side, showing the gummed surface of the paper backing.

Figure 6 is a plan view of the face side of a modified form of pocket mounting device embodying this invention.

Figure 7 is a plan view showing the blank of transparent material employed for the manufacture of such modified form.

In the drawings, 1 indicates a picture to be mounted, and a suitable background sheet or mount is shown fragmentarily at 2. To emphasize the special advantage of the use of transparent material in my improved corner pocket mounting devices, the picture, 1, is represented as having no marginal area, and

the corner devices therefore extend under the overlying areas of the corner pocket fittings or mounting devices shown at 3. This view also represents in dotted outline the portion of each corner pocket fitting which extends under the picture for securement to the mount, 2.

Each of the pocket fittings consists of a portion made of transparent material, such as thin celluloid or "cellophane", and an opaque backing member which serves several purposes, as will presently appear. The transparent material may be formed substantially in accordance with the method outlined in my Patent No. 1,799,221, dated April 7, 1931, for making corner pockets of opaque material, such as paper. That is, the blanks of transparent material may be cut from a continuous strip, as indicated in Figure 2, each blank being shaped as shown in full lines, with similar consecutive blanks, as indicated in dotted lines.

Each blank includes a transverse slit, 4, which is preferably, though not necessarily, angular, with the apex, 5, of the angle at the center line of the strip. The ends of the slit lie respectively in a pair of creases or lines of fold indicated in the blank at 6, 6, extending at right angles to each other, and each substantially at 45 degrees to the center line and to the lateral margins of the strip. The corners of the blank are cut off at diagonal lines, 7, 7, parallel to the dotted lines, 6, 6, while the end of the blank is defined by a transverse line, 8, connecting these oblique lines. The material between the lines, 6, 6, and 7, 7, constitutes a pair of tabs or flaps, 9, which are folded back under the remaining area of the blank, as indicated in Figure 3. The outline of the opposite end of the blank is that which results from cutting another and similar blank with diagonal corner outlines, 7, 7, and the transverse edge, 8, so that this opposite end of the blank includes triangular tabs, 10, at each corner, projecting beyond the middle portion of the margin at 11.

The transparent fitting thus produced, as illustrated in Figure 3, is intended to be applied to the corner of a card or picture by

inserting the corner of the picture through the slit, 4, until its edges stop at the folds at line 7, 7, with the tabs, 9, extending under the picture, and with the area adjacent the end, 11, also underlying the picture or card. This leaves only the portion between the lines of fold, 7, 7, and the slit, 4, exposed at the upper side of the picture and overlying the latter, as shown in Figure 1. However, to facilitate the securement of the fitting to the mount, 2, and also to hold the tabs, 9, in their folded position, I prefer to add to the fitting a backing of sheet material gummed on both surfaces and cut to conform to the outline of the fitting as it appears in Figure 3. The adhesive material on the upper surface of this blank, 12, secures it permanently to the under face of the tabs, 9, and to the under surface of the remaining area of the fitting. The adhesive on the opposite face (the under side) of the blank, 12, is available for securing it in place on the mount, 2. And by forming the transparent blank with an aperture, 13, in the area between the slit, 4, and the edge, 11, I expose a sufficient portion of the gummed upper surface of the part, 12, at 14, so that, if desired, this exposed area, 14, may be moistened for securement of the corner fitting to the back surface of the picture to be mounted, thus providing a permanent engagement of the picture in the fitting.

The transparent material may be folded closely enough so that the corner fittings will be held frictionally in place when applied to the corners of a card or picture, and by thus placing them and moistening the under surface of the backing material the picture may be positioned, as desired, on the mount, 2, and the corner fittings may be pressed down for permanent securement thereto. This will leave the picture removably held by the corner fittings, but if it is to be permanently secured the exposed gummed areas at 14 may be utilized, as already described, when the fittings are originally placed on the picture; or, after they have been secured to the mount, the picture may be temporarily removed while these areas are moistened, so that when it is replaced it may be pressed firmly down over said areas and thus permanently fastened.

Figure 6 illustrates a somewhat simpler design of corner pocket in which the transparent material comprises a triangular area, 20, intended to overlie the corner of the card or picture which it holds, while flaps, 21, are folded back at the lines, 22, so as to extend under the card or picture. The lines of fold, 22, 22, extend at right angles to each other, forming the corner of the pocket, while the third edge, 23, of the triangular area, 20, is diagonally disposed, preferably at 45 degrees to each of the fold lines, 22. Each of the flaps, 21, is also in the form of a triangle, one of whose edges is the line of fold at 22, while its

adjacent edge, 24, is equal in length to said edge, 22. The third side of this triangle, 25, is equal in length to the side, 23, of the area, 20, and these edges, 25, of the two triangular flaps, 21, abut each other when the flaps are 70 folded under the area, 20, as illustrated in Figure 6. The pocket is completed by securing to the under faces of the flaps, 21, a square of gummed paper or the like which is treated with adhesive on both its under and 75 upper surface, so that the exposed under surface is adapted for securement of the pocket to a card or mount like that shown in Figure 1. In Figure 6 this square of paper is completely covered by the two abutting triangular 80 flaps, 21, except for the area of an aperture, 26, formed by the registering notches in the edges, 25, of the flaps, which thus leaves exposed a small area of the adhesive on the upper surface of the gummed paper which 85 may be utilized in the same manner as the gummed area shown at 14 in Figure 4, namely, for securing the card or picture permanently in the pocket.

The transparent material for the corner pocket shown in Figure 6 may be quite simply cut from a continuous strip or ribbon, as indicated in Figure 7, each blank consisting of the triangular area, 20, and the two associated triangles, 21, previously termed flaps. 95 If desired the blanking die which cuts this trapezoidal piece from the strip may include means for impressing or scoring in the piece the lines of fold, 22, 22, or the material may be handled by automatic machinery for completing these folds, and also for applying the gummed backing sheet thereto. 100

I claim:

1. A corner pocket of transparent sheet material combined with a backing sheet, said transparent material comprising an area having two adjacent edges at right angles with flaps of the material folded under said area adjacent said edges and secured to the backing sheet; said area having a slit disposed diagonally with respect to said edges to receive the corner of a picture card or the like, and the backing sheet being gummed on its under side for securement to a mount. 105

2. A corner pocket of transparent sheet material combined with a backing sheet, said transparent material comprising an area having two adjacent edges at right angles with continuous portions of the material folded under said area adjacent said edges, the said area having a slit disposed diagonally with respect to said edges to receive the corner of a picture card or the like, so that the corner portion of said card underlies said area of the transparent material adjacent the folded edges and overlies the remainder of said area, the backing sheet being gummed on both surfaces, whereby its upper surface is secured to the transparent material and its under surface is adapted for securement to a mount, 110 115 120 125 130

the aforesaid portion of the transparent material which underlies the card being apertured to expose the upper gummed surface of the backing sheet to permit adhesive securing thereof to the back of the card.

3. A corner pocket of transparent sheet material comprising an area having two adjacent edges at right angles, with portions of said material folded under said area adjacent said edges, said area having a slit disposed diagonally with respect to said edges to permit the insertion of the corner of a picture card or the like, with the corner portion underlying the transparent material adjacent the folded edges and overlying the remainder of said area, said area being apertured, and the transparent corner pocket being adhesively secured to sheet material gummed on its upper surface, whereby a portion of said gummed surface is exposed through such aperture for securing directly to the card.

4. A corner pocket of transparent sheet material comprising an area having two adjacent edges at right angles, with flaps of the material folded under said area adjacent said edges, said area having a slit disposed diagonally with respect to said edges to permit insertion of the corner of a picture card or the like, so that said corner lies under the transparent material adjacent the folded edges thereof, and overlies said material at the other side of the slit, the flaps being dimensioned to completely underlie the area bounded by the slit and the folded edges of the pocket to form a smooth surface for the reception of the corner of the card.

5. A corner pocket of transparent sheet material comprising an area having two adjacent edges at right angles, with flaps of the material folded under said area adjacent said edges, said area having a slit disposed diagonally with respect to said edges to permit insertion of the corner of a picture card or the like, so that said corner lies under the transparent material adjacent the folded edges thereof, and overlies said material at the other side of the slit, the flaps being dimensioned to extend from said folded edges beyond the diagonal slit and to lap under the area of the material which the card overlies.

6. A corner pocket mounting device composed of a piece of transparent sheet material having two adjacent edges at right angles along which the material is folded upon itself providing space for the insertion of the corner of a picture card or the like with its adjacent edges stopped by said folds, and with a portion of the transparent material overlying the face of the card, together with a single backing sheet of paper or the like gummed on both sides for adhesive securing respectively to the transparent material and to a mount.

7. A corner pocket of transparent sheet material comprising a right angle triangular area with flaps folded thereunder along the legs of the triangle, and projecting beyond the hypotenuse, and a backing sheet of paper or the like gummed on both sides with the flaps adhesively secured to one side.

8. A corner pocket of transparent sheet material having two edges at right angles with flaps of the material folded under the area adjacent said edges, and a backing sheet of paper or the like gummed on both sides with said flaps adhesively secured to one side of said backing sheet, the other side being adapted for securing to a mount.

9. A corner pocket mounting device composed of a piece of transparent sheet material having two adjacent edges at right angles along which the material is folded upon itself, providing space for the insertion of the corner of a picture card or the like with its adjacent edges stopped by said folds, and with an unbroken triangular portion of the transparent material overlying the face of the card, the two folded edges constituting two sides of said triangle, and the card being introduced by insertion under the third side, the material which is folded under said triangle extending beyond said third side and lying under the card, and means for securing said underlying portion of the material to a mount.

10. A corner pocket composed of sheet material and comprising a right-angle-triangular area with flaps folded thereunder along the legs of the triangle and projecting beyond the hypotenuse, and a backing sheet gummed on both sides having one side adhesively secured to the flaps, leaving its opposite side exposed for adhesive securing to a mount.

11. A corner pocket of sheet material having two edges at right angles with flaps of the material folded under said area adjacent said edges, and a backing sheet gummed on both sides with said flaps adhesively secured to one side of said sheet, the other side being exposed for securing to a mount.

12. A corner pocket of sheet material comprising an area having two adjacent edges at right angles with flaps of the material folded under said area adjacent said edges, the said area having a slit disposed diagonally with respect to said edges to permit insertion of the corner of a picture card or the like so that said corner lies under said sheet material adjacent the folded edges thereof and overlies said material at the other side of the slit, the flaps being dimensioned to completely underlie the area bounded by the slit and the folded edges of the pocket to form a smooth surface for reception of said corner of the card.

13. A corner pocket mounting device composed of a piece of sheet material having

two adjacent edges at right angles along which the material is folded upon itself, providing space for the insertion of the corner of a picture card or the like with its adjacent edges stopped by said folds, and with a portion of said sheet material overlying the face of the card, together with a single backing sheet of paper or the like gummed on both sides for adhesive securement respectively to the said sheet material and to a mount.

14. A corner pocket mounting device composed of a piece of sheet material having two adjacent edges at right angles along which the material is folded upon itself, providing space for the insertion of the corner of a picture card or the like with its adjacent edges stopped by said folds, and with a portion of sheet material overlying the face of the card, together with a single backing sheet of paper or the like gummed on both sides for adhesive securement respectively to the sheet material of the pocket and to a mount, said pocket material being shaped to cover less than the entire outwardly disposed area of the gummed sheet, whereby the exposed portion of said area is available for securement directly to the card.
